DESIGN FOR LACE OR THE LIKE

Oscar F. Schicker, Teaneck, N. J.

Application February 15, 1935, Serial No. 55,438

Term of patent 7 years

To all whom it may concern:

Be it known that I, Oscar F. Schicker, a citizen of the United States, residing at 644 Tilden Avenue, Teaneck, Bergen County, New Jersey, have invented a new, original, and ornamental Design for Lace or the like, of which the following is a specification, reference being had to the accompanying drawing, forming a part thereof.

The figure is a plan view of a piece of the lace showing my new design.

I claim:

The ornamental design for lace or the like as shown.

In testimony whereof I have signed this specification.

OSCAR F. SCHICKER.
